UNITED STATES PATENT OFFICE.

FRANK L. O. WADSWORTH, OF PITTSBURGH, PENNSYLVANIA, ASSIGNOR TO ENAMELED METALS COMPANY, OF SHARPSBURG, PENNSYLVANIA, A CORPORATION OF PENNSYLVANIA.

CONDUIT FOR ELECTRIC WIRES.

1,247,756.

Specification of Letters Patent. Patented Nov. 27, 1917.

Application filed June 27, 1916. Serial No. 106,130.

To all whom it may concern:

Be it known that I, FRANK L. O. WADSWORTH, a citizen of the United States, and resident of Pittsburgh, in the county of Allegheny and State of Pennsylvania, have invented a new and useful Improvement in Conduits for Electric Wires; and I do hereby declare the following to be a full, clear, and exact description thereof.

10 My invention pertains to thread-protectors for use in connection with the screw-threaded units of conduit or other pipe, to protect the threads from the coating material during the coating operation, and to protect 15 such threads from damage during shipment. The invention is particularly applicable to thread protectors of the general type disclosed in McIlroy Patent No. 1,120,731, in which a fragile sleeve is placed over the 20 threads before enameling, so as to prevent the enamel from entering the threads and also to form a protector for preventing damage to the threads during transit to the place where the conduit or pipe is to be used. It 25 is the principal object of the present invention to provide a means for permitting such a fragile sleeve to be removed quickly when desired. It is another object of my invention to provide a means for enabling a fragile 30 thread-protector to be removed easily, which means will be of so simple a nature as not appreciably to increase the cost of production of the thread-protected conduit units.

35 A thread-protector constructed in accordance with my invention is described, by way of example, in the following specification, and shown in the accompanying drawing. It is to be understood, however, that the invention may be embodied in other ways, and that changes may be made in the form described and shown, without exceeding the 40 scope of the invention, as defined in the appended claims.

45 In the drawing:

Figure 1 is a plan of the end of a conduit unit provided with a thread-protector constructed in accordance with my invention;

50 Fig. 2 is a sectional elevation of the same, the section being taken on the line 2-2 of Fig. 1, looking in the direction of the arrows; and

55 Fig. 3 is a view similar to Fig. 1, but showing the thread-protector as employed in connection with a metallic cap.

Referring to the drawings, 10 indicates a portion of conduit or other pipe, having threads 11 at the end thereof. The threads are covered by a sleeve 12 formed of fragile material, such as paper, cardboard or the like. This sleeve is placed in position before the enameling operation; so that all those threads which are beneath the sleeve are protected from the enamel, and, when the sleeve is removed, these threads are left clean and ready for the easy placing of a coupling or the like thereon. The sleeves 12 are usually left in position during transit, and are removed by the workmen at the last moment, when it is desired to install the pipe. In this way the sleeves prevent physical damage to the threads during shipment of the pipe from place to place.

It is very desirable that the time taken in removing the protecting sleeves be reduced to the utmost possible extent. To this end, according to my invention, I insert a flexible member between the sleeve 12 and the threads 11. When the sleeve is to be removed, the end of this flexible member is seized and pulled upon, which results in the sleeve being torn lengthwise, and thus readily coming off the threads. In the form of my invention here illustrated, this flexible member consists of a wire 13, which is disposed between the sleeve 12 and the threads 11, which wire has an end 14 which projects rearwardly along the pipe. At the front end, the wire 13 is bent over and back to form a clip 15 which engages upon the outside of the sleeve 12.

The wire 13 is put in place, with the sleeve 12, before the enameling operation. When it is desired to remove the sleeve 12, the free end 14 of the wire 13 is seized and pulled toward the end of the pipe. The result of this is that the sleeve 12 is torn along the line of the wire 13, whereupon the sleeve readily comes off the pipe. The clip 15 at the end of the wire 13 effectually prevents the wire 13 from being pulled through between the sleeve and the threads, instead of performing its tearing functions.

In some instances, a metallic cap 16 (Fig. 3) is placed over the end of the sleeve 12, to prevent the same from being prematurely broken owing to violent treatment in transit. In this case, the wire 13 is put in position as before explained, and thereafter the cap 16 is put in place over the clip 15 and the end 110

of the sleeve 12. When the threads are to be exposed, the cap 16 is first torn off and the sleeve 12 is then removed by means of the wire 13, as above explained.

It will readily be seen that the device described enables the protecting sleeve to be removed from the conduit with an expenditure of time so small as to be inappreciable. Moreover, this result is accomplished with nothing more than an extremely slight addition to the cost of applying the protecting sleeve.

Having thus fully described my invention what I claim as new and desire to secure by Letters Patent is:

1. The combination with a threaded pipe, and a sleeve of relatively soft material for protecting the threads thereof, of a flexible member of relatively hard material interposed between the threads and said sleeve, said flexible member having an exposed end extending along said pipe and means for preventing said flexible member from being pulled through, between the threads and said

sleeve, said means comprising a clasp portion formed by bending one end of said flexible member over and back on said sleeve. 25

2. The combination with a threaded pipe, and a sleeve of relatively soft material for protecting the threads thereof, of a flexible member of relatively hard material interposed between the threads and said sleeve, said flexible member having an exposed end extending along said pipe, and means for preventing said flexible member from being pulled through, between the threads and said sleeve, said means comprising a clasp portion formed by bending one end of said flexible member over and back in contact with said sleeve. 30 35

In testimony whereof, I, the said FRANK L. O. WADSWORTH, have hereunto set my hand.

FRANK L. O. WADSWORTH.
